US00D377732S

United States Patent [19]

Ahern, Jr.

[11] Patent Number: Des. 377,732

[45] Date of Patent: **Feb. 4, 1997

[54] CANISTER TOP

[75] Inventor: Richard B. Ahern, Jr., Akron, Ohio

[73] Assignee: Rubbermaid Incorporated, Wooster, Ohio

[**] Term: 14 Years

[21] Appl. No.: 51,572

[22] Filed: Mar. 13, 1996

[52] U.S. Cl. D7/391; D7/392.1

[58] Field of Search D7/391, 392.1, D7/612, 538, 540, 542; D9/435, 454, 452
